RHEOSTAT WITH ROCKING CONTACTOR

Harold D. Timm, Milwaukee, Wis., assignor to
Allis-Chalmers Manufacturing Company, Milwaukee, Wis.

Application April 8, 1952, Serial No. 281,094

4 Claims. (Cl. 201—48)

1

This invention relates in general to electrical regulating devices and in particular to regulating devices of the variable resistance type.

In rheostats of the rocking sector type, in which an arcuate conductive sector is rocked about a pivot point along a path on an arcuate commutator to the segments of which a plurality of resistance sections are connected, it is necessary to suspend the sector relative to the commutator. Heretofore, one method of such suspension utilized two springs secured to the edges of the sector and to a panel or other suitable mounting means. These springs had their axes aligned when the sector was in a median position to center the sector about a line perpendicular to a line through the axes of the springs. This suspension is suitable for smaller sectors which do not move too great a distance between the median position and either of the extreme positions. However, when larger sectors are utilized, the misalignment of the axes of the springs as the sector departs from the median position produces a substantial moment arm for these springs, especially in the extreme positions of the sector, to produce a torque tending to slip the sector along the commutator. This slipping action results in erratic operation of the device and increased wear on the engaging parts and is therefore very undesirable.

This disadvantage may be overcome by utilizing suspension means for the sector which produce substantially no slipping torque on the sector regardless of the sector size or position. One of the most suitable of such suspension means comprises spring means disposed in a plane parallel to the plane including the pivot point and the path of sector travel and secured to the sector at a point which moves only slightly during the sector movement.

It is therefore an object of this invention to provide a regulating device of the rocking sector type which is rugged, reliable and economical to manufacture.

It is a further object of the present invention to provide improved suspension means for the sector of a rocking sector type regulating device in which substantially no undesirable torques act on the sector.

It is an additional object of this invention to provide improved suspension means for a regulating device of the rocking sector type in which the sector has substantially no tendency to slip on its associated commutator.

Objects and advantages other than those set forth above will be apparent from the following

2

description when read in connection with the accompanying drawing, in which:

Fig. 1 is a view in elevation of one embodiment of the present invention disposed for mounting with the sector axis horizontal;

Fig. 2 is a cross section view taken in the plane of line II—II of Fig. 1;

Fig. 3 is an enlarged view of a portion of the sectional view of Fig. 2;

10 Figs. 4 and 5 diagrammatically illustrate the action of the suspension means of this invention when the sector is in both of its extreme positions; and

15 Fig. 6 illustrates an alternate embodiment of the invention disposed for mounting with the sector axis vertical.

Referring more particularly to the drawing by characters of reference, reference numeral 6 designates a vertical panel which is preferably made of metal and is designed to support a commutator with the cooperating brush and the brush actuating means. The drawing shows only a portion of panel 6 supporting a single commutator comprising a plate 7 of insulating material of suitable shape fastened on panel 6 and covering an aperture through the panel 6. Plate 7 is made of a suitable insulating material, such as laminated synthetic resin or impregnated asbestos, and is provided with a plurality of holes to receive a plurality of conductive studs 10 preferably made of brass, of which only four are shown in Fig. 2 to retain simplicity in the drawing.

20 The studs penetrate through the plate 7 and are fastened therein by means of nuts 11, and are preferably arranged in two adjacent concentric circular rows. The studs carry brackets 12 to support the different sections of a resistor 13 in conductive contact with the studs to thereby permit a variable number of sections of the resistors to be connected in a circuit by means of the commutator. Only two sections of resistors 13 are shown in Fig. 2, but it will be understood that in general each segment of one row is connected with the two adjacent segments of the other row through two sections of the resistor. The studs are knurled on a portion of the length thereof, the projections of the knurled portions engaging with the walls of the complementary holes of plate 7 to thereby prevent the studs from turning when the nuts thereof are tightened. It will be understood that the commutator may be constructed in any other suitable known manner which provides the desired rigidity and insulation.

25 The extensions of all the studs penetrate through the aperture of panel 6 and extend

beyond the surface of the panel, and are arranged in side by side spaced relation, the extensions 14 and 16 being interleaved to form the segments of the commutator which are machined after assembly of the studs to form a contact path.

The commutator above described is more particularly adapted to engage with the arcuate brush portion 20 of a conductive sector 21 adapted to rock on the commutator along a path defined by a notch or groove 22 provided in the commutator as shown in Fig. 3. Arcuate brush portion 20 is preferably made of graphite and the remaining portion of sector 21 is preferably made of light sheet metal provided with a needle point 23 resting in a jeweled cup 24 mounted on a spindle 25 through a spring 26. The spindle may be caused to oscillate by means of a link 27 connected with any suitable known actuating means (not shown), the spindle then imparting to sector 21 a rocking movement along the contact path of the commutator. The sector is connected by means of flexible conductor 28 to an insulated terminal 29 on panel 6 to which one terminal of the circuit to be controlled is connected.

Spring 26 urges sector 21 in contact with the commutator and suitable spring means are provided for centering the sector on the commutator. Such spring means are preferably disposed with their axis in the plane 31 including pivot point 23, the center line of arcuate brush portion 20 of sector 21, and the center line of the contact path. For a horizontal mounting of the device, as shown in Fig. 1, the spring means may comprise a single spring 32 disposed in an opening 33 of sector 21 and secured at one end to an extension or lug 34 of sector 21. The other end of spring 32 is secured to a stud 35 which is in turn secured to panel 6. Spring 32 preferably has its longitudinal axis substantially parallel to the chord between the ends of arcuate brush portion 20 when the sector is in the median position shown in Fig. 1. Spring 32 carries the weight of the sector and acts to center the sector on the commutator at the median position shown in Fig. 1.

As the sector rocks about its point of contact with the commutator in a hypocycloid path and departs from its median position, the axis of spring 32 oscillates about the chord between the ends of arcuate brush portion 20 and gradually departs, but only slightly, from substantial parallelism with the chord between the ends of the commutator. At the extreme position of the sector, as shown in Figs. 4, 5, it will be seen that the end of extension 34 to which spring 32 is secured has moved only slightly from its median position. Spring 32 is thus maintained substantially parallel to the chord between the ends of the commutator. The end of extension 34 has only a negligible amount of movement in any direction so that spring 32 retains substantially the same length and tension at all positions of the sector, thereby producing substantially no torque tending to slip the sector on the commutator. The operation of the sector is thus smooth and dependable. Additionally, by disposing spring 32 in the plane 31 between pivot point 23 and the center line of arcuate brush portion 20, no torque is produced which tends to pull the sector in a direction perpendicular to the desired direction of sector movement.

It will be seen that if arcuate brush portion 20 of the sector is of sufficient width, the spring means may be disposed adjacent to sector 21 along plane 31 without necessitating the provision of an opening in the sector.

In Fig. 6 is shown an alternate embodiment of the invention for vertical mounting of the sector. As shown, an additional spring 40 is provided secured to extension 34 and panel 6 and having its axis aligned with the axis of spring 32 when the sector 21 is in the median position shown. Springs 32, 40 center sector 21 in its median position and operate in a manner similar to that described above for spring 32 alone to produce a minimum of undesired torque on sector 21 in all positions thereof.

Although but two embodiments have been illustrated and described, it will be apparent to those skilled in the art that various changes and modifications may be made therein without departing from the spirit of the invention or from the scope of the appended claims.

It is claimed and desired to secure by Letters Patent:

1. An electrical regulating device comprising an arcuate commutator having a plurality of segments, a resistor having a plurality of sections connected to said segments, supporting means for said commutator, a conductive sector having an arcuate portion forming a brush adapted to rock on said commutator, a spring secured to said supporting means and secured to said sector for centering said sector at a median position in rocking engagement with said commutator, and means for moving said sector in rocking engagement with said commutator in either direction from said median position, said spring having its axis disposed substantially parallel to the chord between the ends of said commutator when said sector is in said median position, said spring being secured to said sector at a single point substantially on the center line of said brush for maintaining said axis substantially parallel to said chord in any other position of said sector to prevent said spring from slipping said sector along said commutator.

2. An electrical regulating device comprising an arcuate commutator having a plurality of segments, a resistor having a plurality of sections connected to said segments, supporting means for said commutator, a conductive sector having an arcuate portion forming a brush adapted to rock on said commutator, a spring secured to said supporting means and secured to said sector for centering said sector at a median position in rocking engagement with said commutator, means for moving said sector in rocking engagement with said commutator in either direction from said median position, said spring having its axis disposed substantially along the chord between the ends of said commutator when said sector is in said median position, said spring being secured to said sector at a single point substantially on the center line of said brush for maintaining said axis substantially along said chord in any other position of said sector to prevent said spring from slipping said sector along said commutator.

3. An electrical regulating device comprising an arcuate commutator having a plurality of segments, a resistor having a plurality of sections connected to said segments, supporting means for said commutator, a conductive sector having an arcuate portion forming a brush adapted to rock on said commutator, spring means secured to said supporting means and secured to said sector for centering said sector at a median position in rocking engagement with said commutator, and means for moving said sector in rocking engagement with said commutator in either direction

from said median position, said spring means being disposed to exert its force on said sector in a direction parallel to the chord between the ends of said commutator when said sector is in said median position, said spring means being secured to said sector at a single point substantially on the center line of said brush to exert its force on said sector in a direction substantially parallel to said chord in any other position of said sector for preventing said spring means from slipping said sector along said commutator.

4. An electrical regulating device comprising an arcuate commutator having a plurality of segments, a resistor having a plurality of sections connected to said segments, supporting means for said commutator, a conductive sector having an arcuate portion forming a brush adapted to rock on said commutator, spring means secured to said supporting means and secured to said sector for centering said sector at a median position in 15

5

rocking engagement with said commutator, and means for moving said sector in rocking engagement with said commutator in either direction from said median position, said spring means being disposed to exert its force on said sector along the chord between the ends of said commutator when said sector is in said median position, said spring means being secured to said sector at a single point substantially on the center line of said brush to exert its force on said sector substantially along said chord in any other position of said sector for preventing said spring means from slipping said sector along said commutator.
